UNITED STATES PATENT OFFICE.

FRANK M. MAYNARD, OF ERWIN CENTRE, NEW YORK.

DESIGN FOR A SPRING CLIP OR TONGS.

SPECIFICATION forming part of Design No. 15,588, dated December 2, 1884.

Application filed September 3, 1884. Term of patent 7 years.

To all whom it may concern:

Be it known that I, FRANK M. MAYNARD, of Erwin Centre, in the county of Steuben and State of New York, have invented and produced a new and original Design for a Spring Clip or Tongs, of which the following is a full, clear, and exact description.

My design for a spring clip or tongs consists, mainly, in a novel configuration of the jaws of the implement, substantially as hereinafter described, and shown in the accompanying drawing.

Reference is to be had to the accompanying drawing, forming part of this specification, which represents a view in perspective of a spring clip or tongs embodying my design.

A B indicate the two crossing limbs of the spring clip or tongs, and A' B' the jaws thereof. S indicates their spring. The jaw A' is of a regular curvilinear shape, having a convex back and a concave face, with an outer-tapering-edge form. Said jaw also has a fork-prong-like appearance, being of an ornamental open-work design, *aa*. The jaw B' is of a like open-work design, *bb*, on its face and back, but is of an irregular configuration, being of a slow or flattened curvature, as at *c*, for the greater portion of its length, and of an inward sharp curvature or crooked form at its outer end portion, *d*, in contrast to the regular curva-

ture of the jaw A. The rear portions of the limbs A B are of a straight flat shape or configuration where they cross, terminating by easy curves, as at *e e*, in straight or nearly straight extremities, which are of flattened spread-out configuration at their outer ends, *f f*, as shown.

I claim—

1. The design for a spring clip or tongs, consisting in the jaws A' B', of open-work configuration and of inwardly-curving form, with the one jaw, A', of regular curvature, and the other jaw, B', of irregular curvature, and composed of a slow or flattened curved portion, *c*, and outer sharp curved or crooked portion, *d*, as shown and described.

2. The within-described design for a spring clip or tongs, which consists in the limbs A B, with jaws A' B', of open-work configuration, with the one jaw, A', of regular curvature, and the other jaw, B', of irregular curvature, as at *c d*, and both limbs of straight configuration in rear of the jaws, terminating by curves *e e* in straight or nearly straight extremities of flattened or spread-out configuration at their outer ends, *f f*, as shown.

FRANK M. MAYNARD.
